VARIABLE STROKE PUMP

Giles Philip Eliot Howard, Luton, England

Application June 18, 1948, Serial No. 33,712
In Great Britain May 1, 1947

4 Claims. (Cl. 103—38)

1

This invention relates to variable stroke pumps such as are employed in adding chemicals, in variable amounts, to chemical processes and the like.

The object of the invention is the provision of an improved construction of variable stroke pump which will be strong, durable, easily made and fully satisfactory in operation.

The invention consists broadly of a variable stroke pump comprising a part guided to reciprocate and adapted by its reciprocation to effect the pumping, a lever adapted to oscillate about an axis transverse to the direction of reciprocation of said part, a pivotal connection between said lever and said part, having a pivotal axis parallel to said first named axis, said lever being capable of movement longitudinally of itself relative to one of said axes, whereby oscillation of said lever effects reciprocation of said part, and means for varying the distance between said axes and therefore by varying the stroke of said part.

In order that the invention may be the more clearly understood, certain embodiments thereof will now be described, reference being made to the accompanying drawings wherein:

Figure 1 is a side elevation of a structure in accordance with the invention, comprising a pump together with a driving motor therefor,

Figure 2 is an end elevation of the same looking from the left of Figure 1,

Figure 3 is a sectional side elevation to a larger scale of the pump proper,

Figure 3A is a view of a portion of Figure 3 with the parts shown at a different operative position,

Figure 4 is an end elevation of another structure according to the invention comprising two pumps and a common driving motor,

Figure 5 is a plan of the same,

Figure 6 is a side elevation of the same looking from the left of Figure 4.

Referring first to Figures 1 to 3, and particularly to Figure 3, the pump proper comprises a (say vertically) reciprocating plunger 1 which passes at its lower end through packing 2 held in place by means of a gland 2a into a pump space 1a in the well known way. Said plunger 1 is guided so as to be constrained to reciprocate in a true vertical line. At a point conveniently above the pump space 1a said plunger is connected to a lever 3, whose axis intersects the axis of said plunger, by a connection which as will be hereinafter more particularly described, permits said lever both to slide along its own axis relative to said plunger and to oscillate relative to said plunger about a horizontal axis which passes through the point of intersection of its own axis and that of said plunger. Said lever 3 at one end (on one side of the plunger axis) is pivoted at 4 to a fixed horizontal axis parallel to its axis

2

of oscillation relative to the plunger 1, and at its other end (on the other side of the plunger axis) is actuated by a crank 5 and connecting rod 6 so as to oscillate up and down about the said fixed axis 4. It will be seen that by this oscillation of said lever 3 about said fixed axis 4 the plunger 1 is vertically reciprocated, the lever both oscillating and sliding relative to said plunger during such reciprocation.

As will be hereinafter more particularly described the said fixed axis 4 about which said lever 3 is oscillated is itself capable of being adjusted towards and away from the axis of said plunger 1, said lever sliding longitudinally of its own axis relative to said plunger to accommodate such adjustment. At one limit of such adjustment said fixed axis 4 intersects the plunger axis, as shown in Figure 3A and the amplitude of reciprocation of the plunger 1 is reduced to zero. At the other limit, said fixed axis 4 is relatively remote from said plunger axis, and the point of connection 7 of the lever 3 to the connecting rod 6 is relatively close to said plunger axis. The amplitude of reciprocation of said plunger 1 is therefore a maximum. By adjusting said fixed axis 4 to intermediate positions between said two limits the amplitude of oscillation of the plunger 1 will have intermediate values between zero and the said maximum.

30 More particularly, the aforesaid connection of said plunger 1 and said lever 3 is effected by mounting on the upper end of said plunger a cross head 8 in the form of a massive rectangular frame. A cylindrical trunnion 9 bridges the two opposite upright frame members of said cross head 8 with its ends rotatable in said upright members, and said trunnion has a central transverse hole through it through which said lever 3 passes. This hole and said lever 3 are of circular section as shown in Figure 2. It will be seen that the axis of said trunnion 9 constitutes the axis about which said lever 3 reciprocates relative to said plunger 1 and that at the same time said hole in said trunnion permits of the sliding of said lever 3 relative to said plunger 1 longitudinally of its own axis.

40 A tail rod 10 is rigidly attached to, and extends upwards from, the top of said cross head 8, and said tail rod passes through a fixed guide bearing 11 so as to maintain the plunger 1 in its true vertical axis as aforesaid.

45 In the particular construction being described the adjustable fixed axis 4 about which said lever 3 oscillates is constituted by pivoting the end of said lever to the extremity of an arm 12 projecting rigidly from a sector 13 whose arcuate periphery has worm wheel threads 14 which are in engagement with a worm 15 on a manually operated adjusting spindle 16. The oscillation axis 17 of this sector 13 is parallel to the axis of

the trunnion 9 and to the said fixed axis 4. Said arm 12 extends from one end of said sector 13 so that, as said sector rotates in one direction (counterclockwise according to Figure 3), the end of said arm moves towards said trunnion 9, pushing the lever 3 through the hole in said trunnion, and, as said sector rotates in the other direction, the end of said arm moves away from said trunnion, pulling the lever through said hole. Said arm 12 is so shaped and arranged that when the sector 13 is rotated to the limit in the first named direction, said arm is in line with said lever 3 and extends into the hole in the trunnion 9 to the point at which the said adjustable fixed axis 4 intersects the axis of said trunnion. This is the position of zero reciprocation of the plunger 1 and is illustrated in Figure 3A.

A clamp 18 is provided for locking the sector 13 at any position to which it is adjusted, so that the forces applied to said sector when the pump is reciprocated are not taken by the worm 15 and worm wheel threads 14.

The construction above described enables the stroke adjustment of the pump to be effected by means of parts of simple construction and ample bearing surfaces. The continuously rotating crank 5 is mounted on the output shaft 19 of a geared motor 20.

The pump space 1a communicates by way of a port 21 with an intermediate point of a conduit 22 having an inlet end 23 and an outlet end 24. Suitable one way valves (say ball valves) are provided in said conduit 22 to ensure that fluid flow between the said intermediate point and the two ends can only flow in the appropriate direction.

Describing now certain constructional details, the pump space 1a and port 22 are formed in a relatively massive block 25. Upon this block is mounted a frame structure which carries the upper bearing 11 for the tail rod 10, and also the worm 15 and the sector 13 and associated parts. This frame structure comprises an integral piece consisting of a bottom 26, which is mounted flush on the top of the block 25, and two side walls 27 and 28 upstanding vertically from said bottom 26. On the top of these side walls 27 and 28 is mounted a top piece 29 which is formed with a boss 30 which carries said bearing 11.

These side walls 27 and 28 towards their upper ends are extended horizontally to the left (according to Figures 1 and 3) and at the left extremities of these extensions they are joined by means of horizontal bars 31 and 32 spaced vertically one above the other. These bars carry the bearings for the spindle 16 of the worm 15 as clearly shown in Figure 3. Said spindle 16 is manually rotated by means of a knob 33 at its upper end.

The oscillation axis 17 for the sector 13 is constituted by a fixed pivot pin extending between the walls 27 and 28. Said walls 27 and 28 are formed respectively with bosses 34 and 35 which receive the ends of said pivot pin, and which between them locate said sector 13 axially.

Said sector has an arcuate slot 36 through it, and the aforesaid clamp 18 is constituted by a collar fast on a rod 37 which passes through said slot 36 and screws into a block 38 formed integrally on the inner surface of the wall 27. The wall 28 is, as shown, cut away to make room for said rod 37 and also to give easier access to said sector 13 and worm 15, said rod 37 is provided with a hand knob 39.

It will be seen that, when the rod 37 is screwed

tightly into the block 38, said sector 13 will be clamped tightly between said block 38 and the collar 18. When said rod 37 is slightly unscrewed the sector 13 can be freely actuated by means of the worm 15.

The block 25 is mounted on a pedestal element 40 which in turn is mounted on a base 41, and the geared motor 20 is mounted on a bracket 42 which is also mounted on said base 41. It might, however, be preferred to mount the motor bracket direct on the pump structure somewhat in the same way as in the dual system described below.

Referring now to Figures 4, 5, and 6, these figures illustrate the application of the invention to an arrangement in which two pumps are driven by a common motor. In this arrangement there are two pump structures each of which is identical with the structure illustrated in Figure 3, except that in one of said structures the walls 27 and 28 are right and left instead of left and right. The same references have been applied to Figures 4, 5, and 6 as to Figures 1, 2 and 3 to designate the same parts.

These two structures are arranged in spaced relation side by side with their walls 27 facing each other and their axes 17 coincident, and between said structures is mounted a single geared motor 43 whose output shaft is designated by the reference 44. This shaft 44 is, as shown, parallel to the said coincident axes 17 of the two pump structures and, at its two ends said shaft 44 has cranks 45 mounted on it which are connected, by means of connecting rods 46 to the respective levers 3 at their points 7. Thus the motor drives both pumps.

The two pump structures are mounted on respective pedestal elements 47 which in turn are mounted on a common bar member 48.

The geared motor 43 is mounted on a bracket 49 which in this case is overhead and is secured to a horizontal overhead bridging member 50 which extends between the two walls 27 of the pump structures. As will be clear from the drawing this bridging member 50 is formed with two downwardly depending lugs 51 which are secured flush to the respective walls 27 of the pump structures.

The reference 52 designates additional strengthening elements by which the geared motor is secured to the two pump structures.

It will be appreciated that, in the arrangement of Figures 4, 5 and 6, each pump remains independently adjustable by the manipulation of its adjusting knob 33 and its clamping knob 39.

It will be readily understood that the number of pumps which could be driven by a common motor is not limited to two. A multiple pump unit may obviously be constructed by utilising the requisite number of pump structures and connecting the output shaft of a common geared motor to the levers 3 of said pump structures by means of respective crank and connecting rod connections. As in the case of the double unit each pump will remain independently adjustable.

I claim:

1. A variable stroke pump comprising an element guided to reciprocate in a straight line, and adapted by its reciprocation to effect the pumping, a fixed part, a lever, a pivotal connection connecting said lever to said fixed part, means for oscillating said lever about said pivotal connection, a trunnion rotatably mounted on said element, the said trunnion being formed with a hole therethrough, said lever slidably extending

through said trunnion hole, whereby oscillation of said lever effects reciprocation of said element, and means for adjusting said fixed part for sliding said lever longitudinally in said hole, thereby varying the stroke of said element, said adjusting means being operable to bring said pivotal connection into said trunnion hole, thereby adjusting the stroke of said element to zero.

2. A variable stroke pump comprising a plunger element and having one end in a pump space, means guiding said plunger element to reciprocate a cross head rigidly secured to the other end of said plunger element, a tail rod rigidly secured at one end to said cross head and extending from said cross head coaxially with, and in a direction away from, said plunger element, means guiding said tail rod to reciprocate, a trunnion rotatably mounted in said cross head, a fixed part, a lever, a pivotal connection connecting said lever to said fixed part, means for oscillating said lever about said pivotal connection, said lever passing slidably through a hole in said trunnion, whereby oscillation of said lever effects reciprocation of said plunger element, and means for adjusting said fixed part for sliding said lever longitudinally in said hole and thereby varying the stroke of said plunger element, said adjusting means being operable to bring said pivotal connection into said trunnion hole, thereby adjusting the stroke of said element to zero.

3. A variable stroke pump comprising an element guided to reciprocate in a straight line and adapted by its reciprocation to effect the pumping, a rotatable sector having worm teeth on its arcuate surface, a rotatable worm in mesh with said worm teeth, an arm extending rigidly from said sector, a lever, a pivotal connection connecting an end of said lever to the end of said arm, means for oscillating said lever about said pivotal connection, a trunnion rotatably mounted on said element, said lever passing slidably through a hole in said trunnion, whereby oscil-

lation of said lever effects reciprocation of said element, rotation of said sector by said worm causing said lever to slide in said hole in said trunnion and thereby vary the stroke of said element, said sector having a position at which the end of said arm extends into said hole in said trunnion thereby adjusting said stroke to zero.

4. A variable stroke pump comprising an element guided to reciprocate in a straight line and adapted, by its reciprocation to effect the pumping, a rotatable sector having worm teeth on its arcuate surface, a rotatable worm in mesh with said worm teeth, a lever, a pivotal connection connecting said lever to said sector, means for oscillating said lever about said pivotal connection, and a second pivotal connection connecting said lever to said element, said second pivotal connection permitting said lever to slide longitudinally of itself relative to said second pivotal connection, whereby oscillation of said lever effects reciprocation of said element, and rotation of said sector by said worm causes variation of the stroke of said element.

GILES PHILIP ELIOT HOWARD.
